(57) **CLAIM**

I claim the ornamental design for a reversible plush toy, as shown and described.

DESCRIPTION

This application is related to U.S. patent application Ser. No. 15/849,493 filed Dec. 20, 2017 and titled “Reversible Toy”, which is hereby incorporated by reference in its entirety for all purposes.

FIG. 1 is an isometric view of a reversible plush toy according to a first embodiment and showing the reversible plush toy in a first configuration.

FIG. 2 is a front elevation view of the reversible plush toy of FIG. 1.

FIG. 3 is a rear elevation view of the reversible plush toy of FIG. 1.

FIG. 4 is a left side elevation view of the reversible plush toy of FIG. 1.

FIG. 5 is a right side elevation view of the reversible plush toy of FIG. 1.

FIG. 6 is a top plan view of the reversible plush toy of FIG. 1.

FIG. 7 is a bottom plan view of the reversible plush toy of FIG. 1.

FIG. 8 is an isometric view of the reversible plush toy of FIG. 1 in a second configuration.

FIG. 9 is a front elevation view of the reversible plush toy of FIG. 8.

FIG. 10 is a rear elevation view of the reversible plush toy of FIG. 8.

FIG. 11 is a left side elevation view of the reversible plush toy of FIG. 8.

FIG. 12 is a right side elevation view of the reversible plush toy of FIG. 8.

FIG. 13 is a top plan view of the reversible plush toy of FIG. 8; and,

FIG. 14 is a bottom plan view of the reversible plush toy of FIG. 8.

The differently stippled areas indicate different color surfaces of the reversible plush toy but are not intended to indicate specific colors.

The broken lines illustrate unclaimed portions of the reversible plush toy that form no part of the claimed design.
